O. RÖSEKE.

ALARM CLOCK WITH PRECEDING ALARM.

APPLICATION FILED JUNE 11, 1919.

1,424,213.

Patented Aug. 1, 1922.

OTTO RÖSEKE
BY Lawrence Langner

UNITED STATES PATENT OFFICE.

OTTO RÖSEKE, OF STUTTGART, GERMANY.

ALARM CLOCK WITH PRECEDING ALARM.

1,424,213.

Specification of Letters Patent. Patented Aug. 1, 1922.

Application filed June 11, 1919. Serial No. 303,493.

(GRANTED UNDER THE PROVISIONS OF THE ACT OF MARCH 3, 1921, 41 STAT. L., 1313.)

To all whom it may concern:

Be it known that I, OTTO RÖSEKE, residing at Stuttgart, Wurttemberg, Germany, have invented certain new and useful Improvements in Alarm Clocks with Preceding Alarms (for which I have filed an application in Germany February 9, 1918, Patent No. 311,741), of which the following is a specification.

10 Alarm clocks heretofore known have had the disadvantage that their alarms started suddenly with full vigor consequently frightening the sleeper to awaken him. This is disagreeable and in addition disturbs others 15 who need not awaken at the same time.

In order to prevent these inconveniences, the alarm clock according to the present invention has been provided with a preliminary alarm which preferably gives single 20 alarm signals, or strokes of the bell, before the main alarm. These single alarm signals are sufficient to cause ordinary people to awake gradually so that they will not be frightened out of their sleep. Further the 25 preliminary alarm permits the person awakened by it to disable the main alarm before it becomes operative and thus prevent others sleeping close by from being awakened by the main alarm.

30 This preliminary alarm, according to the present invention, may operate some time before the operation of the main alarm, for instance, ten minutes before, and repeat at certain intervals, for instance at every one 35 or two minutes until the main alarm is sounded. Preferably, the signal is a single stroke of the bell, and is so arranged that the intensity of the sound of each stroke increases with repeated strokes. This has the 40 effect of awakening the sleeper gradually and with just as much noise as is necessary according to the soundness of his sleep. With some people, sound sleepers for instance, the preliminary alarm will not arouse 45 them entirely. Nevertheless the preliminary alarm will arouse them sufficiently to prevent the main alarm, which follows the preliminary alarm, from startling them.

The preliminary alarm and the mechanism 50 operated thereby may be conveniently applied to existing forms of alarm clocks, particularly since the mechanism for operating the alarm may be set in motion by any suitable moving part of the main alarm controlling mechanism. It has been found ad-

vantageous to cause the preliminary alarm to be controlled by the time wheel of the main alarm mechanism, which wheel is operated by the time spring of the clock. Therefore, it is not necessary to provide an extra spring for this preliminary alarm, with the advantageous result that there is not another spring to be periodically rewound. 60

In the accompanying drawings which show by way of example one form of the present 65 invention,

Figure 1 is a rear elevation showing parts of the alarm clock.

Fig. 2 is a similar view, the initial or preliminary alarm having just been put in 70 operation.

Fig. 3 is a top plan view of the alarm mechanism.

Fig. 4 is a side view of the same.

Figs. 5^a, 5^b, and 5^c show various positions 75 of a part of the mechanism for controlling both the initial and main or final alarms.

Fig. 6 is a side view on an enlarged scale of the settable alarm controlled mechanism.

The time works of the alarm clock may 80 be of any suitable or known construction.

The initial or preliminary alarm of the present invention comprises a lever *a* which is pivoted on a screw *b* and is appropriately fitted with two arms, one arm bearing a 85 striker or hammer *c* adapted to strike against the bell *d* of the clock, and the other arm carrying a peg *e* which extends close to the face of a gear-wheel *g* which carries plugs *f* to cooperate with the peg *e*. The wheel *g* is 90 an intermediate wheel to be found in all clocks, either in the form shown or its equivalent, and is continuously rotated under the influence of the time works spring of the clock. The number of plugs *f* and their relative spacing corresponds to the number of 95 repeated operations of preliminary alarms and the time interval between alarms. In the illustrated embodiment there are four of such plugs *f* each of which gives a signal 100 or alarm every one or two minutes.

In operation, when the clock is set for preliminary alarm, the plugs *f* engage the pegs *e* of the lever *a* during the rotation of the wheel *g* successively and at the desired interval. The lever *a* is thereby raised, as shown in Fig. 2, until the plug *f* has glided from under the peg *e*. The lever *a* is then 105 free and can drop freely, or forcibly, under the influence of a spring, to thus cause the 110

hammer *c* carried by the lever *a* to strike against the bell *d* of the clock and give the preliminary alarm. The falling of the lever *a* can be controlled by a spring *h* to vary the blow of the hammer against the bell as will be hereinafter described.

Normally the preliminary alarm is disconnected or inoperative and is only connected to become effective or operative at a predetermined time, about ten minutes, before the operation of the main alarm. The preliminary alarm, according to the present invention, is connected to become operative by the cam mechanism of the main alarm which is operated by the time works of the clock. This cam mechanism is shown in the accompanying drawings as comprising a disk *m* geared by the gear *p* as is usual, to the time works of the clock; a regulator shaft *o*; and a regulating pin *n*. The disk *m* is held in normal engagement with the pin *n* by a spring *l* as is usual, so that as the pin *n* enters a drop or notch *q* in the disk *m*, the entire disk and the spring *l* will move laterally. When the pin *n* rests in the base of the drop, the spring *l* permits the main alarm to operate in the usual manner. The drop *q* is not abrupt as in ordinary alarm clocks but is sloped. This sloping of the drop is employed not only to make the preliminary alarm effective, but also controls the intensity of the blow of the hammer *c* against the bell. For this purpose the lever *a* of the preliminary alarm is arranged to be engaged by a spring controlling member *i* having an abutment *k* for engaging the lever *a* and preventing the operation of the hammer *c* by holding the lever *a* in its highest position out of range of the plugs *f* on the operating wheel *g*. When the pin *n* starts down the sloping surface of the notch *q*, the spring *l*, which engages the spring *i* moves gradually from normal position and thus moves the controlling member *i* to remove the high part thereon from the lever *a*. This takes place about ten minutes before the operation of the main alarm, and as a consequence of this movement of the abutment *k*, the lever *a* is permitted to drop down to position to be engaged by the plug *f* on the wheel *g*. As the wheel *g* rotates the lever *a* is raised and dropped as above described. The dropping movement of the lever *a* is, however, interrupted by the abutment *k* and in the first stages of the preliminary alarm operation this dropping movement of the lever *a* is slight. The disk *m* of the alarm mechanism continues to move laterally thus moving the abutment *k* which increases the extent of dropping movement to the lever *a* and consequently the hammer *c*. The slight dropping movement of the lever *a* permits the hammer *c* to strike the bell of the clock very lightly. As the operation repeats the increased dropping movement of the lever *a*

causes the hammer *c* to strike the bell with more force and therefore a loud sound results. This continues in intensity until finally the main alarm is put in operation as above described.

Any suitable or known device may be employed for making the alarm ineffective either after the sleeper has been awakened or when it is not desired.

I claim as my invention:

1. An alarm clock comprising time mechanism, impact mechanism settable to produce alarms; and settable mechanism controlled by the time mechanism for automatically modifying the force of impact during the operation of the alarm.

2. In an alarm clock, time mechanism, means for giving periodic alarms at predetermined intervals; and means controlled by the time mechanism for altering the nature of the alarm from the first period to the last period.

3. In an alarm clock, time mechanism, means for giving periodic alarms at predetermined intervals; and means controlled by the time mechanism whereby the intensity of the alarm increases from the first period to the last period.

4. An alarm clock comprising time mechanism, impact mechanism settable to produce periodic alarms, and settable mechanism controlled by the time mechanism for automatically modifying the force of impact during the operation of the alarm.

5. In an alarm clock, means for giving periodic alarms; means whereby the alarm of the first period is of less intensity than the alarm of the last period; and means for giving a continuous alarm after the last period of said periodic alarms.

6. An alarm clock comprising alarm mechanism having means for causing alarms to be given intermittently at predetermined intervals, and means for automatically effecting a prolonged alarm after a predetermined number of preliminary alarms.

7. An alarm clock having alarm mechanism settable to operate at a predetermined time and having a continuous alarm device and an intermittent alarm device, and means for automatically effecting the operation of the continuous alarm device at a predetermined time after the first operation of the intermittent alarm device.

8. In an alarm clock, time mechanism, alarm mechanism; settable mechanism for causing the alarm mechanism to commence to operate at a predetermined time; and means controlled by the time mechanism for altering the nature of the alarm during the operation of the alarm device.

9. In an alarm clock, time works; main alarm mechanism comprising means settable to determine the time when the alarm shall be operated; means controlled by the time

works of the clock for causing the alarm to operate at the determined time; and a preliminary alarm mechanism comprising means controlled by the last named means for controlling the operation of the preliminary alarm.

10. In an alarm clock, a preliminary alarm mechanism comprising an alarm operating lever, a hammer carried by said lever, and a peg carried by said lever; time works comprising a gear-wheel; and plugs carried by said gear-wheel and adapted to engage the peg carried by the alarm operating lever to move said lever in preparation to giving an alarm and to subsequently release said lever to cause the alarm to be given.
11. In an alarm clock, a preliminary alarm mechanism comprising an alarm operating lever, a hammer carried by said lever, a peg carried by said lever, and an abutment controlling said lever; time works comprising a gear-wheel; plugs carried by said gear-wheel and adapted to engage the peg carried by the alarm operating lever to operate said lever repeatedly at predetermined intervals for a predetermined period; and means moving said abutment to permit the operation of the alarm operating lever differentially during the progress of said alarm period.
12. In an alarm clock, preliminary alarm mechanism comprising an alarm operating lever, a hammer carried by said lever, a peg carried by said lever, and an abutment controlling said lever; time works comprising a gear-wheel; plugs carried by said gear-wheel and adapted to engage the peg carried by the alarm operating lever to operate said lever repeatedly at predetermined intervals for a predetermined period; and a cam disk for controlling said abutment to permit the movement thereof to free the alarm operating lever for operation, said cam disk having a beveled surface whereby the freedom of movement of the alarm operating lever is varied during the progress of the alarm period.

13. In an alarm clock, means for producing at a predetermined time single stroke

alarms repeated at predetermined intervals and means for altering the nature of the alarm from the first interval to the last interval.

14. In an alarm clock, means for producing at a predetermined time single stroke alarms repeated at predetermined intervals and means whereby the intensity of the alarm increases from the first interval to the last interval.

15. In an alarm clock, time mechanism; alarm mechanism; preliminary alarm mechanism; and a common controller for directly controlling the two said alarm mechanisms.

16. In an alarm clock, time mechanism; preliminary alarm mechanism; alarm mechanism comprising a time wheel and a controller operated by the time wheel; and means on said controller for controlling the preliminary alarm.

17. In an alarm clock, time mechanism; preliminary alarm mechanism comprising means operated by the time mechanism for actuating the preliminary alarm mechanism; and alarm mechanism comprising means operated by the time mechanism for controlling the alarm mechanism and the preliminary alarm mechanism.

18. In an alarm clock, time mechanism; preliminary alarm mechanism comprising a hammer and means for actuating the hammer; alarm mechanism comprising a time wheel and a controller for the alarm mechanism, said controller having a sloping lug thereon engaging the hammer, said time wheel being adapted to permit the gradual movement of the controller and the lug to bring various portions of the sloping lug into engagement with the hammer whereby the force of impact of the hammer is gradually increased.

In testimony whereof I hereby affix my signature in presence of two witnesses.

OTTO RÖSEKE.
